Otto S. Drake.

John J. Thompson ATTORNEY

UNITED STATES PATENT OFFICE.

OTTO S. DRAKE, OF NEWBURGH, NEW YORK.

SPEAKER UNIT.

Application filed July 18, 1927. Serial No. 206,472.

This invention relates to a magnetic unit of that class which is employed in loud speakers, such are used in the cone type of radio horn, but the invention may be put to many other uses in its present form, and by minor changes in design or mounting to many other uses.

While there have been many instruments of this same kind made, they have had several disadvantages and have been faulty in construction and design and in the method employed for adjusting the air gap and the pole pieces, and while some of them provide means for adjusting the air gap, said means is of such a crude nature that in locking the adjustable parts in place, the fine adjustment is lost, and in fact it is impossible to make a fine adjustment of one or two thousandths of an inch, which is of vital importance for the best results in instruments of this class.

In the design herewith shown, it is possible not only to make and hold a very fine adjustment of the pole pieces with respect to each other, but also to further adjust the armature with respect to the pole pieces, and to lock said adjustments without disturbing the same.

Another object of the invention is to construct an instrument of this kind that shall be simple, strong, contain few parts and be easy of manufacture.

With these and other objects in view, my invention consists in certain construction and combination of parts as will hereinafter be fully described and claimed, and illustrated in the accompanying drawings which form a part hereof and in which like figures of reference refer to corresponding parts in all of the views, and it is fully understood that slight changes may be made without departing from the spirit of the invention.

The device is known as the balanced type, where the translating coil is in two parts, one half on each side of the armature which is secured near its center and operates between two sets of air gaps, thus producing a very sensitive instrument, also the driver pin which transmits the movement from the armature to the cone, does so with a straight line and compound movement.

In the drawings:—

Figure 1 is a top plan view of the instrument, with the exception of the cone and bracket or other means for mounting the same, which is not shown.

Figure 2 is an end view of the same, with the driver pin partly cut off.

Figure 3 is a cross sectional view taken on the line A—A of Figure 1.

Figure 4 is a transverse view of the same with one of the coil spacers and one of the permanent pole pieces removed.

Figure 5 shows an exploded view of the several parts making up the unit.

Figure 6 is a top plan view of one of the permanent pole pieces.

Figure 7 shows the method employed in assembling the armature to the armature bar.

Referring to the drawings—

It is to be understood that while the usual horse-shoe magnet 10, is shown, that this permanent magnet may be of any desired shape or form, of one piece, or built up.

To the ends thereof, one to the upper side and the other to the lower side are attached by the screws 11 and nuts 12, the two permanent pole pieces 13 of suitable material, which are formed with the notches 14, and the screw holes 15 and 16.

Secured to said permanent pole pieces 13 by the screws 17 through the holes 16 and at right angles therewith are the brass coil spacers 18, which are L-shaped, and which are provided with the alined bearings 19 and the slots 37, and the coil spacer pins 20.

The armature assembly, comprising the two alined armature adjusting plugs 21, which are secured to the ends of the armature bar 22, of suitable material such as phosphor bronze, by brazing or otherwise securing to said plugs; and the armature 23 being formed with the notches 24 (see Fig. 7) near its center which are adapted to receive the locking tongues 25 which have been formed on the bar 22 adjacent to the hole, 24 and which are pressed down into said notches 24 holding the armature rigid to the bar 22 and at right angles therewith.

The above assembly is mounted with the plugs 21 in the bearings provided in the brass coil spacers 18 and are held therein in a locked position by one of the screws 17 which is threaded into the part 26 of said spacer 18, and passes through a clearance hole in the part 27 of the same spacer which is divided into these two parts by the saw cut 37 communicating with the bearing 19, to provide a grip on the plug 21 in said bearing, and in this way the plugs 21 may be turned in said bearings 19, by the use of a spanner.

wrench (not shown) which will enter the transverse holes 28 in said plugs 21, and in this manner the armature 23, may not only be rocked to adjust the air gaps but also adjusted lengthwise, and when so adjusted, it is locked by tightening the screws 17.

The adjustable pole pieces 29 are made up of laminations U-shaped and riveted together to form said pole pieces 29, which are mounted as follows.

The permanent pole piece 13 is secured in abutting relation to the brass coil spacer 18 by the screws 30, passing through said spacer 18 and threaded into the pole pieces 13; which leaves the notches 14 in an alined and parallel relation with the armature 23, and as said notches 14 are slightly narrower than the thickness of the pole pieces 29, so that said pole pieces 29 having been placed 20 with their legs in said notches 14, and slid in until their ends give the proper air gap, the screws 30 are tightened which will draw the parts 18 and 13 together to press on and hold said adjustable pole pieces 29 in place, 25 and by loosening said screws 30, the air gap may be adjusted by tapping in on the pole pieces 29 to lessen the gap, or by pulling out to widen the gap, and again clamping by the screw 30, and in this manner not only 30 fine adjustment is gotten, but said adjustment can not get out of adjustment during the locking of the parts.

The coils 31 are mounted within the space formed by the permanent pole pieces 13 and 35 the brass spacers 18, and surround the armature 23, and are spaced apart by the pins 20, and their leads 32 may be brought out to any suitable binding posts on the frame (not shown).

40 For transmitting the movement of the armature 23 in a compound manner to increase its power, but in a straight line movement, there is secured to one end of said armature 23 a connector rod 33, which 45 passes through a hole in the end of the vibrator 34, and which is soldered therein.

Said vibrator 34 is of resilient material 50 and has its rear end bent to form a spring which is secured by the screw 35 to the upper adjustable pole piece 29, and has secured thereto and adjacent to said rod 33 and parallel therewith a driver pin 36 the outer 55 end of which may be connected to the apex of a cone speaker in the usual manner, and which may be of any suitable length.

Having thus described my invention, what I claim as new and desire to secure by Letters Patent, is:—

1. In a device of the class described, a 60 magnet, a pair of permanent pole pieces carried by said magnet, a pair of coil spacers having one end rigidly attached to one of said permanent pole pieces and the other end adjustably secured to the other permanent pole piece, said coil spacers formed

with alined bearings, an armature mounting adjustably mounted therein and means for locking said adjustment, a pair of adjustable pole pieces mounted at right angles to said permanent pole pieces and adapted to be held between said permanent pole pieces and said coil spacers with their ends forming an air gap with said armature, and means for transmitting movement from said armature. 75

2. In a device of the class described, and in combination with a magnet, of a pair of permanent pole pieces carried thereby and in parallel relation with each other, a pair of L-shaped coil spacers having one of their 80 ends secured at right angles to said permanent pole pieces, and the other end adjustably secured in abutting relation to the other permanent pole piece, a pair of U-shaped adjustable pole pieces mounted in alined relation with each other and at right angles to said permanent pole pieces and held in an adjustable manner between the abutting ends of said permanent pole pieces and said coil spacers, said coil spacers formed with alined 85 clamp bearings, a pair of axial alined plugs mounted therein in an adjustable manner, an armature bar having its ends rigidly secured in said plugs, an armature secured at right angles to said bar, and a pair of 90 actuating coils surrounding each end of said armature and contained within the coil space and in spaced relation with each other. 95

3. In a device of the class described, and in combination with a magnet, of a pair of permanent pole pieces having one of their 100 ends secured to said magnet, a pair of L-shaped coil spacers having their body portion secured at right angles to one of said permanent pole pieces and their foot portion secured in an adjustable manner to the 105 end of the other permanent pole piece, coil spacing pins secured to the body portion of said coil spacers on the same vertical plane, said coil spacers formed with an alined bearing, an armature, an armature bar secured at right angles therewith and having its ends mounted in said bearings, means for adjusting said bar in said bearings, means for clamping said bar in said bearings, a pair 110 of laminated pole pieces mounted in the same vertical plane with their ends forming an air gap with said armature and held in rigid and adjustable manner by said permanent pole pieces and said coil spacers, a 115 vibrator mounted adjacent to one end of said adjustable pole pieces, a driver pin carried thereby, a rod having one end secured thereto and the other end secured to said armature, and a pair of actuating coils mounted 120 within said coil space and surrounding the ends of said armature. 120

4. A speaker unit of the class described, comprising a magnet, a pair of permanent pole pieces, one placed above said magnet 130

and the other below said magnet with their rear ends secured thereto, a pair of L-shaped non-magnetic coil spacers having one of their ends rigidly secured to and at right angles to one of said permanent pole pieces, and their other ends secured in clamping relation with the other permanent pole piece forming a coil space, a pair of laminated pole pieces mounted in the same vertical plane and held in adjustable and clamped relation by said permanent pole pieces and said coil spacers, said non-magnetic coil spacers formed with an alined bearing and a saw-cut portion connecting therewith, a pair of plugs slidably and rotatably mounted in said bearings, and means for clamping the same therein, an armature bar carried by said plugs, an armature secured at right angles to said bar and in spaced relation with the ends of said adjustable pole pieces, and means for adjusting the air gap between said pole pieces and said armature, coils mounted within said coil space and surrounding said armature, and means for transmitting vibrations from said armature.

5. A speaker unit of the class described, comprising in combination with a permanent magnet, of a pair of permanent pole pieces having their rear ends secured to the ends of said magnet, a pair of non-magnetic spacers having one of their ends attached at right angles to one of said permanent pole pieces and the other end adjustably secured to the other permanent pole piece, a pair of adjustable pole pieces secured to the ends of said permanent pole pieces at right angles therewith and on the same vertical plane with their ends in spaced relation with each other, an armature mounted in the same vertical plane as said adjustable pole pieces and in spaced relation thereto, means for adjusting said spaced relation between said pole pieces and between said pole pieces and said armature, and means for locking said adjustment, and a pair of coils mounted in the field of said magnet and said pole pieces.

In testimony whereof I hereunto affix my signature.

OTTO S. DRAKE.
